CLAIM

The ornamental design for a cover for a recessed light fixture, as shown and described.

DESCRIPTION

FIG. 1 is a top perspective view of the cover for a recessed light fixture.

FIG. 2 is a bottom perspective view of the cover.

FIG. 3 is a side view of the cover, the cover appearing substantially identical from all sides, with the exception of the four projecting tabs.

FIG. 4 is a top view of the cover.

FIG. 5 is a bottom view of the cover; and,

FIG. 6 is a top perspective view of the cover installed in a recessed light fixture.

The broken lines in FIG. 6 illustrates environmental subject matter and forms no part of the claimed design.
